UNITED STATES PATENT OFFICE.

GEORGE WATKINSON, OF NEW HAVEN, CONNECTICUT, ASSIGNOR TO THE
L. CANDEE & CO., OF SAME PLACE.

DESIGN FOR OVERSHOES.

Specification forming part of Design No. **11,516**, dated November 18, 1879; application filed October 15, 1879.
[Term of patent 7 years.]

To all whom it may concern:

Be it known that I, GEO. WATKINSON, of New Haven, in the county of New Haven and State of Connecticut, have invented a new Design for Overshoes; and I do hereby declare the following, when taken in connection with the accompanying drawing and the letters of reference marked thereon, to be a full, clear, and exact description of the same, and which said drawing constitutes part of this specification, and represents a side view.

This invention relates to a design for overshoes, and particularly to that class which have a foxing and border at the edge of plain varnished rubber, the intermediate portion of the upper embossed to imitate other material; and the invention consists in the design hereinafter described, and shown in the accompanying illustration.

The foxing and edge are of the usual shape, and shown in solid black in the illustration. The intermediate portion of the upper is embossed in what is commonly termed "basket-pattern."

Across the front of the upper several ribs, *a*, are formed, more or less in number, and these being varnished give a highly ornamental and finished appearance to the shoe.

I claim—

The design for overshoes, consisting of the basket-pattern upper and ribs *a* across the front, as shown and described.

GEORGE WATKINSON.
